UNITED STATES PATENT OFFICE

CARL F. HAAS, OF SOUTH BEND, INDIANA, ASSIGNOR TO WESTINGHOUSE ELECTRIC AND MANUFACTURING COMPANY, A CORPORATION OF PENNSYLVANIA

DESIGN FOR A FINIAL FOR LIGHTING FIXTURES OR SIMILAR ARTICLES

Application filed June 16, 1930. Serial No. 36,059. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for a Finial for Lighting Fixtures or Similar Articles, of which the following is a specification, reference being had to the accompanying drawing, constituting a part hereof.

I claim:—

The ornamental design for a finial for lighting fixtures or similar articles substantially as shown.

In testimony whereof, I have hereunto subscribed my name this 28th day of May, 1930.

CARL F. HAAS.
